(57) **CLAIM**

The ornamental design for an external bypass shock absorber, as shown and described.

DESCRIPTION

FIG. 1 is a perspective view of an external bypass shock absorber showing our new design;

FIG. 2 is a right side elevational view thereof;

FIG. 3 is a left side elevational view thereof;

FIG. 4 is a front side elevational view thereof;

FIG. 5 is a rear side elevational view thereof;

FIG. 6 is an enlarged top plan view thereof; and,

FIG. 7 is an enlarged bottom plan view thereof.
